UNITED STATES PATENT OFFICE.

ROBERT RUFFIN, OF COMO DEPOT, MISSISSIPPI.

DRAFTING INSTRUMENT.

SPECIFICATION forming part of Letters Patent No. 614,985, dated November 29, 1898.

Application filed August 18, 1897. Serial No. 648,693. (No model.)

To all whom it may concern:

Be it known that I, ROBERT RUFFIN, a citizen of the United States, residing at Como Depot, in the county of Panola and State of 5 Mississippi, have invented a new and useful Drafting Instrument, of which the following is a specification.

My invention relates to drafting implements adapted for use in various lines of drafting, both general, as in mechanical work, and specific, as in geographical and topographical plotting and in the laying off of maps, obtaining latitude and departure, and in various operations in connection with a plane table, and 15 incidentally in the laying off of timbers in carpentry.

Various objects and advantages of this invention will appear in the following description, and the novel features thereof will be 20 particularly pointed out in the appended claims.

In the drawings, Figure 1 is a view of a drafting instrument constructed in accordance with my invention and designed especially for general work in connection with engineering and plotting. Fig. 2 is a detail view in perspective of the slide and the contiguous portion of the adjustable or hypotenuse arm. Fig. 3 is a detail section showing 25 the connection between the adjustable or hypotenuse arm and the fixed perpendicular or latitudinal arm on line 3 3 of Fig. 1. Fig. 4 is a detail sectional view of the slide and the joint between the same and the adjustable or hypotenuse arm on line 4 4 of Fig. 1. Fig. 5 is a view of a slightly modified and simplified form of the drafting instrument, also 30 adapted for general work, but particularly designed for use in practical carpentry, for laying off roof and other timbers, ascertaining the pitch and length, as well as the terminal, vertical, and horizontal cuts thereof. Fig. 6 is a view of another modified form of 35 the instrument embodying my invention, which is particularly adapted for use in connection with the plane table in geographical and topographical plotting.

Similar numerals of reference indicate corresponding parts in all the figures of the drawings.

In the illustrated embodiment of my invention the essential features are a main or lon-

gitudinal arm carrying a perpendicular fixed latitudinal arm, an adjustable or hypotenuse arm having a sliding and pivotal connection with the main and perpendicular arms, or one of them, and an angle-gage arranged concentric with a pivotal point of the adjustable or hypotenuse arm, in connection with double verniers for accurately measuring fractional parts of lines and angles.

The form of instrument which is illustrated in Figs. 1 to 4, inclusive, comprises a main or longitudinal arm 1, to which is attached or integral with which is formed a fixed perpendicular or latitudinal arm 2, having a longitudinal slot 3, whereby the adjustable or hypotenuse arm 4 is adapted, by means of a locking device, such as a clamp 5, for adjustment at the adjacent end in a direction parallel with said latitudinal arm. The form of clamp illustrated in the drawings consists of a bolt or pivot-pin 6, extending through the slot 3 and a corresponding longitudinal slot 7 in the adjustable or hypotenuse arm and 50 fitted with a thumb-nut 8. The slot 7 in the adjustable or hypotenuse arm provides for linear adjustment of said arm with relation to the fixed perpendicular arm 2, and the use of the pivot-pin 6 provides for pivotal movement of the adjustable or hypotenuse arm with relation to the fixed perpendicular arm 2. The opposite end of the adjustable or hypotenuse arm is pivotally and slidingly mounted upon the main or longitudinal arm 55 1 to provide for the adjustment of the said end of the hypotenuse arm with relation to the main or longitudinal arm to secure any desired angular position of the adjustable arm and any desired lengths of the base, altitude, and hypotenuse of the triangle formed by said main, perpendicular, and adjustable arms. In the construction illustrated the pivotal and sliding connection between the adjustable arm and the main arm is formed 60 by means of a slide 9, fitted for linear adjustment upon the main arm 1 and having an extension or ear 10, (see Fig. 2,) upon which the contiguous extremity of the adjustable arm is pivoted, the slide consisting, essentially, 65 of terminal guide-loops connected by a base-plate 11 below the plane of the main arm and by a vernier 12 above and contiguous to the upper-surface of said main arm. Fur-

thermore, the connection between the adjustable arm and the slide consists of a hollow or centrally-open pivot 13, consisting of an eyelet or any equivalent thereof arranged in such 5 a position with relation to the slide that the fiducial or feather edge of the main arm spans the opening of the hollow pivot and lies accurately above the center thereof, or, in other words, occupies a position in a diametrical 10 plane of the pivot, whereby in applying the instrument to a line or angle for measurement the center of the hollow pivot may be arranged over a given point in sight through the pivot. The center of the hollow pivot is 15 the point at which the inner or operative edge of the adjustable arm 4 intersects the inner or operative edge of the main arm. The function of the vernier in this connection is too well known to need explanation, it being 20 obvious that its zero-point is transversely opposite the point of intersection of the operative edge of the adjustable arm with that of the main arm, or, in other words, is transversely opposite the center of the pivot, and 25 the vernier being of the double type, whereby it may be read in either direction from the zero-point, according to the requirements of the measurement which is being taken. The base-plate 11, from which the ear 10 projects, 30 is spaced from the lower sides of the guide-loops of the slide, as shown in Figs. 2 and 4, to allow the contiguous pivotal extremity of the adjustable arm to operate between the base and the under surface of the main arm, 35 by means of spacing-blocks 11^a.

Carried by the base or other suitable portion of the slide is an angle-gage 14, disposed concentric with the pivot 13 and traversed by the adjustable arm, by comparison with which 40 angles of deflection of the adjustable arm from the main arm may be measured, said angle-gage in the construction illustrated consisting of a quadrant-protractor. It is obvious that while the quadrant-protractor only 45 is illustrated in Fig. 1 the extension thereof to the ordinary form of semicircular quadrant is possible without departing from the spirit of the invention, the advantage of such a modification residing in the fact that other 50 angles than those at the base of a right-angled triangle could be measured, the peculiar construction of clamp which is employed for connecting the adjustable arm to the fixed perpendicular arm providing for the detachment 55 of the former from the latter, and hence providing for swinging the adjustable arm to a position beyond that of a perpendicular to the main or to a position in which its inclination would be from instead of toward the 60 fixed arm 2.

In the construction which I have illustrated in Fig. 5 the instrument is simplified by the omission of the angle-gage to adapt it particularly for use in practical carpentry, an 65 important function of the instrument being in connection with the laying off of roof-timbers and the equivalents thereof. In the con-

struction shown in Fig. 5 the main arm 1^a, slotted perpendicular arm 2^a, adjustable arm 4^a, the clamp 5^a, the slide 9^a, with its vernier 7^a attachment 12^a, and the pivotal connection 13^a between the adjustable arm and the slide are equivalent to the corresponding parts described in connection with Figs. 1 to 4. To give an example of the use of this form of my 75 invention, let it be supposed that it is required to obtain the length of a rafter for a hipped or gable roof having a span of sixteen feet and a rise or altitude of six feet. As each rafter will extend over a horizontal distance of one-half the span, the slide end of the adjustable arm should be arranged to bring the center of the pivot or the zero-point of the vernier over the graduation "8" of the main arm, (eight feet being one-half the span,) 80 and the opposite end of the adjustable arm should be adjusted with relation to the perpendicular arm to arrange the operative edge of the former at the graduation "6" of the latter, whereupon the length of the desired 85 timber—namely, ten feet—will be indicated on the adjustable arm at its point of intersection with the operative edge of the perpendicular arm. If now it is desired to obtain the bevel of the ends of the rafter cut to the 90 desired length, the instrument may be used as a bevel and applied to the timber with the adjustable arm parallel therewith. The edge 95 of the main arm will give the line of the horizontal cut of the timber, while the perpendicular arm will give the line of the vertical 100 or perpendicular cut of the timber.

In the construction which I have illustrated in Fig. 6 the main arm 1^b carries a slotted, fixed, or perpendicular latitudinal arm 2^b, 105 which is extended in both directions from the main arm, and an adjustable arm 4^b, mounted upon a slide 9^b, said adjustable arm being preferably duplicated, as indicated, and each adjustable arm having a coöperating semicircular angle-gage 14^b, carried by the slide. The latitudinal bar 2^b is preferably mounted for sliding movement upon a guide-rib 15, arranged in a fixed position upon the plane table or other surface upon which the instrument is used and graduated to form a double vernier, said rib having terminal clips 16, which overlap the surface of the latitudinal bar and hold the latter firmly against displacement, while allowing adjustment of said 110 bar parallel with its length. Furthermore, the main bar or blade 1^b is preferably graduated continuously from end to end in opposite directions at its upper and lower edges, respectively, and is also provided with a central line of graduations having an initial point at an intermediate part of the bar and being increased in opposite directions from this central point. This construction, in connection with the slide with its vernier 12^b, 115 enables the operator to plot in either direction or from a central point in both directions, and hence enables him to obtain the latitude and departure of a line running in any direc- 120 125 130

tion from either a side or an intermediate initial point. In this form of my invention I preferably provide each adjustable arm with a vernier 17 for use in connection with the 5 angle-gage traversed thereby, and as in geographical and topographical plotting, for which the form of instrument illustrated in Fig. 6 is especially designed, it is ordinarily unnecessary to have the adjustable arm terminally connected to a perpendicular arm or 10 latitudinal bar I preferably construct the adjustable arm 4^b of only sufficient length to extend slightly beyond the peripheries of the angle-gages or protractors.

15 The operation of either of the forms of my instrument in determining the latitude and departure of a roof or "run" will be readily understood by those familiar with the art, it being obvious that the measurements upon 20 the perpendicular arm will indicate the latitude and the measurements upon the main arm the departure when the adjustable arm is arranged to agree with the direction of the line to be measured. In the constructions 25 illustrated in Figs. 1 to 5, inclusive, it is designed to measure latitude and departure by the measurements on the perpendicular and main arms when the adjustable arm is arranged to agree with the run, in which case 30 the length of the run will be indicated upon the adjustable arm; but in the construction illustrated in Fig. 6 it is necessary in order to obtain the latitude and departure of a line to first adjust the slide to arrange the zero- 35 point of the vernier over one terminal of the line and then slide the instrument upon the guide-rib 15 a sufficient distance to bring the operative edge of the main arm to the other terminal of the line, whereupon the distance 40 between the zero-point of the vernier and the second-named extremity of the line will give the departure, while the latitude will be indicated by the distance through which the perpendicular arm 2^b has been moved, the 45 graduations thereon being compared with the vernier on the guide 15.

Furthermore, it will be understood that while in accurate work it is desirable, and in fact necessary, to employ verniers or the 50 equivalents thereof at the various points indi-

cated, I do not desire to be limited to the use thereof, as any other suitable indicating points may be employed when the definite accuracy necessary in close work in plotting, engineering, &c., is not required; and it is obvious, furthermore, that various other changes in the form, proportion, and the minor details of construction may be resorted to without departing from the spirit or sacrificing any of the advantages of this invention. 55

Having described my invention, what I claim is—

1. A drafting instrument having a longitudinal bar, a slide mounted for adjustment upon said bar and comprising a base arranged below the plane of the bar, terminal guide-loops connected by said base and fitted upon said bar, and a double-vernier bar connecting the guide-loops above the plane of the longitudinal bar, said base being extended to 70 form an ear 10 and an angle-gage 14, and an adjustable arm pivotally mounted upon said ear by means of a hollow pivot, of which the center is in the plane of the fiducial edge of said longitudinal bar, substantially as specified. 75

2. The herein-described drafting instrument comprising perpendicularly-disposed rigidly-connected longitudinal and latitudinal arms 1 and 2, a slide mounted upon the longitudinal arm and having spaced guide-loops connected, contiguous to the plane of the upper surface of the longitudinal arm, by a vernier-bar, said slide carrying an angle-gage, an adjustable or hypotenuse arm 85 pivotally mounted upon said slide and intersecting the latitudinal arm, and means for clamping the hypotenuse and latitudinal arms at their point of intersection, the said hypotenuse arm being adjustable longitudinally, laterally, and angularly with relation to the latitudinal arm, substantially as specified. 90

In testimony that I claim the foregoing as my own I have hereto affixed my signature in 95 the presence of two witnesses.

ROBERT RUFFIN.
